(57) **CLAIM**

The ornamental design for an “open reed game call apparatus”, as shown and described.

DESCRIPTION

FIG. 1 is a perspective view of an open reed game call apparatus according to the present invention;
FIG. 2 is a left side elevation view thereof;
FIG. 3 is a top view thereof;
FIG. 4 is a bottom view thereof;
FIG. 5 is a right side elevation view thereof;
FIG. 6 is a rear elevation view thereof; and,
FIG. 7 is a front elevation view thereof.
